UNITED STATES PATENT OFFICE.

GEORGE O. LEOPOLD, OF PHILADELPHIA, PENNSYLVANIA, ASSIGNOR TO NORTH BRO'S M'F'G CO., OF PHILADELPHIA, PENNSYLVANIA, A CORPORATION OF PENNSYLVANIA.

BENCH-DRILL.

1,087,794.

Specification of Letters Patent. Patented Feb. 17, 1914.

Application filed December 10, 1912. Serial No. 735,972.

To all whom it may concern:

Be it known that I, GEORGE O. LEOPOLD, a citizen of the United States, residing in Philadelphia, Pennsylvania, have invented 5 certain improvements in Bench-Drills, of which the following is a specification.

My invention relates to certain improvements in bench drills and is of the type which is detachably secured to a bench and 10 operated by hand, although it will be understood that the invention can be operated by power if desirable.

The object of my invention is to simplify the construction of a drill of this character, 15 as well as to cheapen its cost of manufacture. I make it automatic in its action and provide means for changing the speed of the drill or for locking the spindle to allow the chuck to be opened or closed.

20 In the accompanying drawings:—Figure 1, is a front elevation illustrating my improved bench drill; Fig. 2, is a side view; Fig. 3, is a sectional plan view on the line *a—a*, Fig. 2; Fig. 4, is an enlarged vertical 25 sectional view through the upper portion of the drill on the line *b—b*, Fig. 1; Fig. 5, is a sectional plan view on the line *c—c*, Fig. 4; Fig. 6, is a sectional plan view on the line *d—d*, Fig. 4; Fig. 7, is a sectional view on 30 the line *e—e*, Fig. 4; and Fig. 8, is a detached perspective view illustrating the change speed mechanism.

Referring to the drawings, 1 is the post of 35 the drill, cylindrical in cross section, as illustrated in Fig. 3, and having an integral clamp plate 2 projecting at the rear thereof and a bracket 3 in which is mounted a clamp screw 4 for securing the drill to a bench or other support.

40 5, 5 are two screws, pointed at one end, and mounted in the clamp plate. After the clamp is secured in position by the clamp screw 4, these pointed screws can be turned so as to be driven into the bench to firmly 45 hold the tool from turning on the screw 4 as a pivot.

On the face of the post 1 is a slotted guide 50 6 adapted to receive a tongue of a sliding bracket 7 having a socket 8 for the stem 9 of the base plate 10 on which the work is mounted.

55 11 is a clamp screw having a T-head adapted to the slot 6 in the post, which is illustrated in Fig. 3, and provided with a nut which bears against the bracket 7 so

that the bracket is held in the position to which it is adjusted by this nut.

The upper end of the post 1 has two bearings 12 and 13 connected by a yoke 14, having a bearing 15 for the main horizontal 60 shaft 16, which is provided with a handle 17 in the present instance. At the inner end of this shaft is a bevel gear wheel 18 having a series of teeth 19 in its periphery and a series of teeth 20 near its hub, as shown by 65 dotted lines in Fig. 2. Mounted in the bearing 12 is a spindle 21 having at its lower end a chuck 22, of any ordinary type, to which the drill is secured. This spindle 21, as illustrated in Fig. 4, passes through a sleeve 42 and two bevel gear wheels 23 and 24. The spindle is slotted longitudinally to receive a key 43 projecting from the sleeve 42 so that the spindle will turn with the sleeve. The teeth of the wheel 23 mesh with the outer 70 teeth 19 of the wheel 18 and the teeth of the wheel 24 mesh with the inner teeth 20 of the wheel 18. Both of these wheels 23 and 24 are loose on the spindle and are clamped thereto by mechanism shown in Fig. 8, and 75 which will be described hereinafter.

On the upper end of the spindle is a feed screw 25, which is held longitudinally thereon by a collar 31 at the lower end and by a cap at the upper end. The spindle is free to 80 turn in the feed screw but must move longitudinally with it. The feed screw 25 is adapted to a threaded opening in the bearing 13 and has at its upper end a ratchet wheel 26 locked to the threaded feed screw 90 25 by means of a ball 27 mounted in a socket in the spindle 21 and in the socket back of the ball is a spring 28. The ball is adapted to a notch 29 in the feed screw, as shown in Fig. 6, so that, under normal conditions, the spindle turns with the feed screw, but if the drill should bind in the material, then the spindle would be uncoupled from the feed screw, as the pressure causes the ball to overcome the pressure of the 95 spring, as a result of which the ball enters the socket and allows the feed screw to turn freely without turning the spindle.

The spindle 21 is grooved at 30 to receive the collar 31 and carried by this collar is a 100 ball bearing 32 on which the end of the feed screw presses so that when the drill is engaged in the work, the pressure of the feed screw 25 is taken by the ball bearing 32.

33 is a guide rod attached to the bearing 110

13 and secured to the lower end of this rod is a head 34, U-shaped to extend on each side of the spindle and above the gear wheel 24. The upper end of the rod passes through a block 35 on the upper end of the spindle 21, and between the upper end of the feed screw 25 and this block, is a pawl carrier 36 pivoted to a post 37 on the block 35 and carrying a spring pawl 38 adapted to engage the ratchet teeth at the upper end of the feed screw 25. This pawl is spring-pressed and has an arm 39 by which it can be turned. The carrier 36 is notched at 40 to allow the handle 39 to drop into place so as to lock it when adjusted to feed either to the right or to the left, but when the handle is in the mid-position, the pawl itself is withdrawn, as illustrated. The carrier is rocked on its pivot 37 by a cam projection on the spindle 21, which is made by notching the spindle, as illustrated in Fig. 5, and placing therein a roller 41. The opening in the carrier is of such a size and shape that, as the spindle turns, the roller will rock the carrier on its pivot 37. When, however, the pawl is not engaged with the ratchet teeth 36, it will turn the feed screw a certain distance at each revolution of the spindle.

The gear wheels 23 and 24 are clamped to the spindle 21 by the mechanism I will now proceed to describe.

The sleeve 42 has a longitudinal slot and two transverse slots, Fig. 8, adapted to receive the double fingered pawls 44. The pivot projections 45 of these pawls rest in the transverse slots.

46 is the shifter having a pin 47 which projects through a cover plate 48 and through the inclosing casing 49. The shifter 46 is in the form of a spring and when shifted into the central position, the fingers of both pawls are in engagement with the ratchet teeth 50 and 51 on the hubs of the two gear wheels 23, 24, respectively, but when it is moved into the lower position, the lower pawl is in engagement with the ratchet wheel 50 and the upper pawl is moved out of engagement with its ratchet wheel 51. The spindle is then driven at high speed through the medium of the teeth 19 on the gear wheel 18 and the pinion 23. When the shifter is moved to the upper position, then the upper pawl engages the teeth of the ratchet wheel 51 and the lower pawl is clear of the ratchet wheel 50; the spindle being driven at a slow speed through the teeth 20 on the wheels 18 and 24.

It will be seen from the above description that I am enabled to make an exceedingly simple and practical bench drill in which the change gearing and ratchet feed mechanism are mounted on the spindle. The change speed gear is such that the spindle can either be driven at a slow speed or at a high speed, or when the shifter is moved

to the central position the spindle is locked so that the chuck can be opened or closed without turning the spindle. Furthermore, the ratchet or feed mechanism is mounted so as to move bodily with the spindle and is actuated on the rotation of the spindle. The frame is simplified by having the lower head, which retains the gearing on to the bearing 12, secured to the guide rod which is also used as a guide for the ratchet feed mechanism.

The change speed mechanism illustrated and described forms the subject of a separate application for patent filed on the 20th day of September, 1912, under Serial No. 799,901.

I claim:

1. The combination in a drill, of a post; bearings on the post; a transverse driving shaft mounted in one of the bearings; a spindle mounted in the other bearing; a sleeve to which the spindle is splined; gearing between the sleeve and the driving shaft; a guide rod secured to the upper bearing and having a head at its lower end embracing the spindle; a block slidably mounted on the upper portion of the rod and secured to the spindle; a bearing collar on the spindle above the head; a feed screw through which the spindle extends resting on the collar and adapted to a threaded opening in one of the bearings of the post; a yielding connection between the feed screw and the spindle; a reciprocating carrier adapted to the head and located between the upper end of the feed screw and the head; a pawl on the carrier; and ratchet teeth on the upper end of the feed screw with which the pawl engages.

2. The combination in a bench drill of a post; means for securing the post to a bench; a table; bearings on the post; a transverse driving shaft mounted in one of the bearings; a spindle mounted in the other bearing; a sleeve to which the spindle is splined; gearing between the sleeve and the driving shaft; a guide rod secured to the upper bearing and having a head at its lower end encircling the spindle; a block slidably on the upper portion of the rod and secured to the spindle; a bearing collar on the spindle above the head; a feed screw through which the spindle extends, resting on the collar and adapted to a threaded opening in one of the bearings of the post; a reciprocating carrier adapted to the head and located between the upper end of the feed screw and the head; a pawl on the carrier; ratchet teeth on the upper end of the feed screw with which the pawl engages; a stop at the upper end of the guide rod for limiting the upward movement of the spindle; and means for yieldingly connecting the spindle to the feed screw.

3. The combination in a drill, of a post having upper and lower bearings; a spindle; a feed screw through which the spindle extends; a bearing collar on the spindle for the end of the feed screw; two bevel gears; clutch mechanism whereby the gears are connected to the spindle; a guide rod secured to the upper bearing of the post and having a head at its lower end embracing the spindle and confining the gears between it and the lower bearing; ratchet mechanism on the guide rod for turning the feed screw; and means on the spindle for actuating the ratchet mechanism. 35
4. The combination in a drill, of a bearing; a feed screw adapted to a threaded opening in the bearing; a spindle extending through the feed screw, said spindle having a bearing collar against which the lower end 40 of the feed screw rests; a guide rod at one side of the spindle and extending parallel therewith; a block on the spindle embracing the guide rod; a carrier adapted to the block at one side of the spindle, the spindle extending through the carrier; a pawl on the carrier; a ratchet wheel on the end of the feed screw with which the pawl engages, the spindle having a recess at the carrier; a roller in the recess adapted to travel in 45 the opening in the carrier to cause the carrier to reciprocate as the spindle rotates; and a yielding connection between the spindle and the feed screw. 50
5. The combination in a drill, of a frame; 55 a vertical spindle mounted in the frame; means for driving said spindle; ratchet feed mechanism consisting of a feed screw through which the spindle extends and having a ratchet wheel at its upper end; a carrier; a block to which the carrier is pivoted; 60 said block being mounted on the upper end of the spindle; a projection on the spindle for actuating the carrier; and a pawl on the carrier arranged to engage the ratchet teeth on the feed screw. 65
6. The combination in a drill, of a spindle; means for rotating the spindle; a feed screw mounted on the spindle and having ratchet teeth; a block mounted on the upper end of the spindle; a guide for the block; a carrier mounted between the block and the feed screw and pivoted to the block and having an opening for the passage of the feed screw; a pawl on the carrier engaging the ratchet teeth of the feed screw; a threaded bearing through which the feed screw extends; a projection on the spindle arranged to engage and to reciprocate the carrier; and friction mechanism carried by the spindle and directly engaging the feed screw. 70

In testimony whereof, I have signed my name to this specification, in the presence of two subscribing witnesses.
